COMBINATION CLOCK AND RADIO-
RECEIVER

Harry R. Van Deventer, New York, N. Y., assignor to Patent Engineering Corporation, a corporation of Delaware

Application April 7, 1932, Serial No. 603,789

11 Claims. (Cl. 250—14)

This invention relates to improvements in a combination clock and radio receiver, and has for its principal object the combination of a clock, preferably one with an electric driving motor, and a radio receiving set including a loud speaker, all assembled and mounted in a single cabinet that is small and compact and that will have the appearance of an ordinary mantel clock, the dimensions of the cabinet being about 6½" wide, 10 6" deep and 10" high.

Another object of the invention is to produce a combination device of the type described in which the chassis carries all of the parts of the radio receiving set including the loud speaker together with the clock mechanism, the entire assembly being readily removable from the cabinet without disassociating or disassembling any of the parts.

Another object is to provide a combination device of the class described in which the tuning dial for the radio receiving set surrounds the clock dial thus giving a tuning dial of greater diameter than is possible if the tuning dial is mounted below the dial of the clock in a set of the dimensions above given.

The invention consists substantially in the construction, combination, location and relative arrangements of parts, all as will be more fully hereinafter set forth, as shown by the accompanying drawings and finally pointed out in the appended claims.

In the accompanying drawings:

Figure 1 is a front elevation of a combination clock and radio set embodying the invention;

Figure 2 is a side elevation of the set, Figure 1;

Figure 3 is a rear view, partly in section, of the set shown in Figures 1 and 2;

Figure 4 is a side elevation, partly in section, of the set shown in Figures 1 and 2;

Figure 5 is a horizontal sectional view on the line 5—5 of Figure 3;

Figure 6 is a rear view of the chassis of the set, Figure 1, with parts removed in order to more

clearly show a sub-assembly mounted thereon comprising the tuning condenser for the radio receiving set and its connections to the tuning dial and the associated electric clock mechanism; and

Figure 7 is a typical circuit which may be used with the combination clock and radio receiving set shown in the other figures.

For the sake of illustration, the invention will be described as applied to a combination clock and radio receiver of the type above referred to, and although the invention will be completely

disclosed herein and specific details of a preferred embodiment thereof disclosed, it must be understood that such details are not intended to be limitative of the invention except in so far as set forth in the accompanying claims. For example, the clock may be dispensed with and the set still further reduced in size and yet retain some of the advantages and objects as more fully hereinafter set forth. 5

The numeral 10 denotes a cabinet which may 10 be made of wood or other suitable material. In the front of this cabinet is an opening 11 for the clock and the dial knobs of the radio set as hereinafter described. The cabinet also has two openings 12 and 13 in the sides thereof to permit egress of sound from the loud speaker. These openings may be covered by a cloth 14 to prevent the ingress of dirt and the cloth may be protected by a grille 15.

The cabinet does not have any operating parts 20 secured thereto, all of the operating parts hereinafter described being mounted upon a framework or chassis 16 which may be of aluminum or other suitable material, and of any desired construction. It may be made from a flat stamping formed to the desired shape. 25

The sides of the framework extend downwardly and are bent outwardly to form the supporting feet 17—17, and when in place in the cabinet these feet may be secured therein by any suitable catch members or by screws. 30

The framework has a horizontally disposed cross bar 18 secured to the sides thereof in any suitable manner and two or more inwardly projecting lugs 19—19. The sub-assembly plate 20 35 is secured to the cross bar and the lugs 19—19 as shown in Figure 6. An outer face of this plate may constitute the clock dial or the clock dial is secured thereto in any suitable manner.

The plate 20 also carries a ring 21 which supports the usual bezel in which the usual crystal is mounted, the ring, bezel and crystal serving to enclose the usual hour, minute and second hands denoted by the numerals 22, 23 and 24. 40

To the back of the plate 20 is secured the posts 45 25—25 which support a bearing for the shaft 26 of the clock movement, said shaft extending rearwardly as shown in Figure 4 and terminating in the usual setting knob 27, whereby the clock hands can be set in the usual manner. The 50 supports 28 are also secured to the plate 20 and support the clock mechanism of any desired type, generally denoted by the numeral 29. For the sake of illustration, an electric clock movement is shown. 55

A horizontally disposed cross member 30 is secured to the sides of the framework 16 in any suitable manner and supports the tuning condensers of the radio set. Any suitable number 5 of tuning condensers may be used and in connection with the circuit shown in Figure 7 two condensers are employed as shown at 31, 32, each condenser comprising the usual framework supporting fixed plates and bearings for the condenser shaft 33 which is common to both condensers. 10

Secured to the inner end of this shaft is the L-shaped member 34 which extends inwardly towards the clock dial and has a notch 35 in its lower end which engages a pin 36 riveted into the carrier plate or ring gear 37. A slot 38 is provided in the sub-assembly plate 20 so that the pin 36 may move therein and the arc of travel of the ring gear 37 limited thereby. 15

The ring gear 37 is provided on its outer edge with teeth and meshes with the gear 39 which is secured to a sleeve 40 to which is attached the knob 41. By turning the knob the ring gear 37 will revolve about the ring 21 which forms a support therefor and will carry with it the arcuate member 42 secured thereto. This member is made of celluloid or other translucent material bearing suitable indicia as commonly used on tuning dials in radio receivers. 20

An opening 43 is provided in the plate 20 and a lamp 44 is mounted immediately behind this opening so that the light from this lamp can shine through the opening and pass through the translucent member 42. 30

A front plate 45 has an opening 46 therein which exposes a portion of the arcuate translucent dial member 42. 35

In addition to the tuning condensers 31, 32, other parts of the radio receiver may be mounted on the cross member 30; for example, the radio frequency transformers 47—47 of the pre-selector and other small parts hereinafter referred to in connection with Figure 1. 40

A heavy base plate 48 is provided secured to the sides of the framework 16 and below this base plate is suitably and insulatedly mounted the piezo-electric crystal 49 which is provided with a pair of clamps 50—50 which have outwardly extending portions 51—51 that pass through suitable openings in the side walls of the framework 16 and engage the lower edges 52—52 of the diaphragm 53. The lower edges of the diaphragm may be provided with stiffening members in order to insure a good contact between the outer ends 51 of the clamps and the diaphragm material, and the diaphragm 53 may be supported on posts 54—54 at the top of the chassis framework as shown. 50

It will be seen from the foregoing that the diaphragm completely surrounds the side walls and top of the chassis and it, together with its driving member (which in this embodiment of the invention is the piezo electric crystal) are mounted upon and carried by the chassis and are removable from the cabinet 10 therewith. The theory and operation of a piezo electric crystal when used in connection with a loud speaker of this description is known and will not be herein described in detail but it is desirable that the base plate 48 be very rigid in order that all of the vibrations of the crystal may be transmitted to the diaphragm and that none of the energy will be lost in the base plate. 60

A circuit which may be used in a combination clock and radio set as herein described is shown 70

in Figure 7 by way of illustration, but any suitable circuit may be employed. It will be understood that all of the parts and instrumentalities necessary in connection with this circuit are mounted upon the chassis and are removable from the cabinet 10 as a unit. 5

An antenna binding post 55 is insulatedly mounted upon the chassis for connection to the antenna, and the binding post 56 is mounted upon and electrically connected to the framework 16 10 to which the grounded side of all the apparatus shown in Figure 7 is connected. 10

The radio frequency transformers 47—47 are connected to the variable condensers 31, 32 as shown, and the resultant pre-selector circuit is 15 connected to the R. F. amplifier 57 which in turn is connected to the R. F. transformer 58 which is connected to the grid of the second R. F. amplifier tube 59, the output of which connects to the R. F. transformer 60, the output of which is connected to the grid of the detector tube 61. The detector tube plate circuit connects to the grid of the first audio amplifier tube 62, the plate circuit of which is connected to the primary of the input push-pull transformer 63, the secondary of which is connected to the grids of the amplifier tubes 64, 65. The plates of the amplifier tubes 64, 65 are connected to the primary of the output transformer 66, the secondary of which is connected to the piezo electric crystal 49. The by-pass condensers 67 are connected from the ground to the plates of the respective amplifier tubes and a resistance 68 is provided in the plate circuit of the detector tube. 30

A filament voltage transformer 69 is provided having its primary connected to binding posts 70 or to a suitable cord and plug whereby connection may be made to a suitable source of current. 35

The clock motor 29, when an electric clock is used, is connected directly across the incoming current supply so that the clock will not stop when the switch 71 is operated. 40

This switch 71 is preferably combined with a potentiometer 72 which serves as a volume control, this potentiometer being connected to the shaft 73 having on its outer end a control knob 74. When the control knob 74 is turned all the way to the left, switch 71 is operated. When turned clockwise the switch is turned on by the first movement of the knob and from there on the resistance of the potentiometer is varied, thereby varying the volume of the set in the usual manner. 45

A rectifier tube 75 has its filament connected as shown to one winding of the transformer 69 in order to supply rectified current to the plate circuit, the same passing to the plates via the choke coil 76 and the resistances 77, 78 and 79 whereby various desired voltages are taken off to the tubes in a known manner. The return circuit for the plate supply current is lead via the plate of the rectifier tube to one side of the incoming current supply, the other side of which is grounded through the condenser 80. 50

The filaments of all of the tubes are energized from a winding of the transformer 69 as shown and across this same winding is connected the lamp 44 for illuminating the condenser dial. 70 This lamp acts as a pilot light as it will only light when the switch 71 is on and the radio set is in use. A center tap resistance 81 is connected across the filament supply wires in the usual manner. 75

The various parts as described are all mounted upon and within the chassis or framework 16; for the sake of clarity in connection with Figures 3, 4, 5 and 6 some of the smaller parts herein referred to have not been shown.

The tubes are mounted as shown in Figure 3 and the insulating member 82 is provided with the usual socket terminals for the pin terminals 83 of the tubes and some of the tubes are shielded by means of the metallic shields 84 which are suitably secured to the framework 16. These shields also encase the radio frequency transformers 58 and 60.

The particular type of tube shown in the circuit Figure 7 has an outside grid. It need not be described in detail for the operation of same will be evident to those skilled in the art from a study of Figure 7.

What is claimed is:

20. 1. A radio receiver including a cabinet, a framework having side walls supported in said cabinet, a diaphragm adapted to be vibrated by a driving member, said diaphragm surrounding the side walls of said framework, a driving member for vibrating said diaphragm mounted on said framework and radio means for causing said driving member to vibrate said diaphragm, said means including a variable condenser mounted on said framework above said driving member.

30. 2. A radio receiver including a cabinet having a base, a framework, adapted to support parts of the radio receiver mounted in said cabinet above the base thereof, a diaphragm within said cabinet surrounding the walls of said framework and having an edge extending downwardly towards the base of said cabinet, means for vibrating said diaphragm mounted in the lower portion of said framework below the main vibratory portion of said diaphragm and radio means for actuating said last means mounted upon said framework.

35. 3. In a radio receiver including a cabinet having a base, a framework supported in said cabinet above the base thereof, a diaphragm having an edge extending downwardly toward the base of said cabinet, said diaphragm being supported by said framework, means for vibrating said diaphragm secured to the downwardly extending edge thereof and supported on said framework, a rigid metallic plate supporting said last means secured to the bottom of said framework above the base of said cabinet, and radio means for operating said first means secured to said framework.

40. 4. A radio receiver including a cabinet, a framework adapted to support parts of the radio receiver supported in said cabinet, a rigid plate secured to the bottom of said framework and forming the bottom closure thereof, a piezo electric crystal secured to said plate, a diaphragm positioned above said plate secured to said crystal and adapted to be vibrated thereby, and means mounted upon and within said framework for receiving radio impulses and for actuating said piezo electric crystal to vibrate said diaphragm, said means including a variable condenser secured to said framework and removable from the cabinet therewith.

45. 5. A radio receiver including a cabinet having openings in its sides, a framework removably supported in said cabinet, a plate closing the bottom of said framework, a piezo electric crystal secured to said plate, a diaphragm mounted on said framework secured to said crystal and adapted to be vibrated thereby, said diaphragm extending around the inner side walls of said

cabinet and having free vibratory portions adjacent the openings therein, and means for receiving radio impulses mounted upon and within said framework adapted to actuate said piezo electric crystal, said means including a variable condenser mounted upon said framework and removable from the cabinet therewith.

5. 6. A radio receiver including a cabinet, a framework removably positioned in said cabinet, a piezo electric crystal mounted on said framework, a diaphragm carried by said framework and covering practically all of the area of the side walls and top of said cabinet and positioned between the inner walls of the cabinet and the outer walls of said framework, means carried by said framework for radio reception and for actuating said crystal, said means including a tuning condenser and a volume control, said condenser and control means having shafts extending through a wall of said cabinet whereby said condenser and volume control may be manually operated.

10. 7. A radio receiver including a cabinet having a front wall, a framework positioned in the cabinet having a sub-assembly plate adjacent the front wall of the cabinet, an electric clock mechanism mounted upon said plate, tuning condensers carried by said framework and mounted in the rear of said clock mechanism and having a shaft parallel to the shafts of said clock mechanism, a plurality of vacuum tubes mounted subjacent said 20 condensers, a shaft mounted upon said sub-assembly plate and projecting outwardly from the front wall of said cabinet, a gear on said last shaft, a gear supported on said sub-assembly plate meshed with said first gear, means connected 25 with said last gear and to the shaft of said condensers, radio means mounted upon said framework including a loud speaker mechanism and connections between said clock mechanism and said radio current supply means whereby said 30 clock and said radio receiver may be operated from a common source of current.

15. 8. A combination clock and radio receiver comprising a cabinet having openings in each side and the front thereof, a framework adapted to fit within said cabinet, an electric clock secured to the front of said framework and adapted to fit in the opening of said cabinet, a loud speaker supported on said framework having its diaphragm adjacent the side openings in said cabinet, radio receiver parts mounted upon said framework and adapted to actuate said loud speaker, control means mounted upon said framework and extending through the front of said cabinet and adapted to control the volume of said 45 loud speaker, and a circuit including a source of current connected to said chassis and adapted to furnish current to said radio receiver parts and said electric clock.

20. 9. In a radio receiver, a chassis comprising a framework having a horizontally disposed cross member therein, a sub-assembly secured to said member and framework, said sub-assembly including an electrically driven clock, tuning condensers for the radio receiver, and means for operating said condensers including a tuning dial connected thereto and movable therewith.

25. 10. In a radio receiver, a chassis comprising a framework having horizontally disposed cross members therein, a sub-assembly secured to said framework including a horizontally disposed plate, an electrically driven clock mounted on said plate, a tuning condenser mounted on said plate, a dial for the condenser connected thereto and operable therewith carried by said plate, a base 30

plate for the chassis, loud speaker driving means mounted on said base plate, and a diaphragm connected to said driving means and supported on said chassis.

5 11. A radio receiver comprising a cabinet having a removable chassis therein supporting parts of the radio set and a sub-assembly adapted to be mounted upon said chassis and removable therefrom as a unit, said sub-assembly compris-

ing a horizontal plate member adapted to be secured to the chassis, said plate supporting an electrically operated clock, a tuning condenser, and means for adjusting said tuning condenser including a dial visible from the front of the cabinet when the chassis is in said cabinet, said sub-assembly and the aforesaid parts mounted thereon being removable as a unit from the chassis.

HARRY R. VAN DEVENTER.
